[57] CLAIM

The ornamental design for a photo identification locket, as shown and described.

DESCRIPTION

FIG. 1 is a top plan view of a photo identification locket showing my new design;

FIG. 2 is a bottom plan view thereof;

FIG. 3 is an end elevational view thereof (looking from bottom to top in FIG. 1), the opposite side being a mirror image;

FIG. 4 is an end elevational view thereof (looking from right to left in FIG. 1), the opposite side being a mirror image;

FIG. 5 is a top perspective view thereof; and,

FIG. 6 is a bottom perspective view thereof.

The broken line showing the chain links in FIGS. 1 and 2 is for illustrative purposes only and forms no part of the claimed design.
